UNITED STATES PATENT OFFICE

2,490,563

RADIO SUPPORTING BRACKET FOR
MOTORCYCLES

Grant L. Van Gastle, Columbus, Ohio

Application September 27, 1946, Serial No. 699,927

2 Claims. (Cl. 250—14)

1

My invention relates to radio receptacles, and more particularly to receptacles of the type adapted for the support of radios upon vehicles.

The primary object of my invention is to provide a receptacle for radio-receiving sets which may be easily and conveniently installed upon the handle bars of motorcycles or other cycle vehicles.

Another object of my invention is to provide a receptacle of this type which embodies an exteriorly mounted metallic housing for the loud-speaker of an associated radio-receiving set, which housing serves, in addition to its normal supporting and amplifying functions, as an antenna for the associated radio.

It is a further object of my invention to provide a cycle mounting for radios which is compact and occupies but little installation space upon the ordinary handle bars of a motorcycle, and which eliminates a separate and usually cumbersome antenna and its associated wiring mechanism.

These and additional objects and advantages of my improved cycle mounting for radios will become more apparent with reference to the following description and accompanying drawing wherein:

Fig. 1 is a front elevational view of my improved radio receptacle mounted on the handle bars of a motorcycle;

Fig. 2 is a side elevational view thereof;

Fig. 3 is a detailed vertical sectional view taken along the line 3—3 of Fig. 1;

Fig. 4 is a transverse vertical sectional view taken through the upper portion of the radio cabinet and through the speaker housing.

Referring now to the drawing, it will be seen that my improved cycle mounting embodies a pair of depending connection brackets 10 which are rigidly secured at their lower ends, by means of threaded bolts 11, at a suitable position upon the lower members of the handle bars 12 of a motorcycle or bicycle. The upper ends of the brackets are bent backwardly to lie in a substantially horizontal plane, and are further bent to form U-shaped clamps 13 which fit around the lower curved surface of the cross member 14 of the handle bars. The upper flat surfaces of the brackets 10 are provided with apertures on either side of the clamps 13, through which are passed the ends of threaded bolts 15. The latter pass through a substantially horizontally disposed rectangular bed plate 16 to rigidly secure the same upon the upper portion of the brackets.

Spaced from the outer edges of the bed plate 55

16 are four strips of angle iron which form perpendicularly disposed rectangular outer flanges 17; one leg of the angle iron strips being rigidly secured, by riveting or by welding, to the bed plate 16; the other leg being provided with a series of threaded holes adapted to receive a like number of cooperatively threaded screws 18. The bed plate 16 is adapted, by means of these screws, to detachably receive the lower open end of a rectangular radio cabinet 19, which is of such a size as to fit snugly around the flange 17. With the cabinet 19 positioned upon the bed plate 16, a relatively enclosed box-like structure is obtained, in which may be positioned the various components of a radio receiving set.

The walls of the cabinet 19 are provided at suitable positions with openings through which the various manual controls of a radio set may pass to join with rotatable control knobs, as indicated at 20. The upper wall of the cabinet is provided with a centrally disposed circular opening 21 whose periphery is covered by an annular collar 22 formed from rubber, synthetic resin, or any suitable electrical insulating material.

A parabolic speaker housing 23 is positioned above the cabinet 19, and is provided with a depending hollow shaft 24 which extends inwardly of the cabinet through the insulating collar 22. The shaft is formed with an enlarged circular flange 25 approximately intermediate its length which serves as a positioning and retention collar for the speaker housing. The lower end of the shaft 24 is screw-threaded, as at 26, and receives a cooperatively threaded clamp nut 27 to firmly maintain the housing upon the cabinet. Interposed between the clamp nut 27 and the insulating collar 22 is a circular metallic washer 28 which is formed with an outwardly projecting arm 29. This arm is provided with circuit-connection screw 30 which is adapted to receive the end of an antenna lead of a radio. It will be seen, in view of the above relation of parts, that antenna current will be conducted through the washer 29, the shaft 24, and ultimately through the entire parabolic housing 23 which serves as an entity as the antenna of an associated radio set.

The supporting shaft 24 of the speaker housing 23 is formed with an axially disposed bore which opens at either end internally of the housing 23 and within the cabinet 19. Through the bore is passed the lead wires 31 of a loud speaker unit 32. The wires 31 are suitably insulated from the metal of the shaft by a cylinder of bond-

ing and shielding material 33, as shown in Fig. 4, which material will extend out of either end of the bore of the shaft.

The loud speaker 32 is mounted within the parabolic housing 23 in a manner so as to completely insulate it from the metal of the housing, as for example as shown in Fig. 4, the housing is provided at its face with an inwardly projecting circular flange 34, which carries an annular rubber washer 35 which resiliently supports the outer circular edge 36 of the speaker cone. The washer 35 is held in position by a metallic ring 37 rigidly joined with the inwardly projecting flange 34 of the housing. The open face of the speaker and housing is covered by a circular grill plate 38 which may be soldered or welded to the housing proper. It will be manifest that the grill will further increase the area of the antenna to provide additional effective surface therefor.

In operation, the mechanism of a radio-receiving set is suitably anchored to and insulated from the bed plate 16, the same may advisably be cushioned from the plate by resilient packing in order to lessen the jar caused by road shocks. The antenna lead of the radio set is then connected with the circuit screw 30 leading to the housing 23, and the loud speaker leads joined with their associated outlets, at which time the cabinet is snugly positioned around the flange 17 and joined therewith by the screws 18.

In view of the foregoing, it will be seen that the present invention provides both a mechanically efficient and extremely compact mounting for radios which is readily adaptable for attachment with the handle bars of a cycle vehicle, and, when so attached, occupies a readily accessible position in front and below the eye level of the driver. The speaker, serving as an antenna for an associated radio, eliminates excessive and cumbersome wiring or post antenna, and presents an attractive and orderly appearance.

While I have described in detail a preferred form of my invention, it will be manifest that various modifications in design and details of construction may be accomplished without departing from the spirit of the invention or the scope of the following claims.

I claim:

1. A weather-protective housing for radio-receiving sets adapted for mounting upon cycle vehicles and comprising a substantially flat base plate for supporting a radio-receiving set; an open-bottom cabinet including side and top walls detachably carried at the marginal edge portion of said base plate for enclosing a receiving set supported on said base plate; a parabolic metallic loud speaker housing having a bracket portion extending through and secured to but electrically insulated from the top wall of said cabinet and providing an enclosure for the loud speaker of a radio-receiving set carried on said base plate; electrical lead means extending through said speaker housing and the top wall of said cabinet and electrically insulated from both said speaker housing and said cabinet for connecting a loud

speaker enclosed in said speaker housing with the speaker circuit of a receiving set carried upon said base plate; and terminal means electrically connected with the bracket portion of said speaker housing for connecting the antenna circuit of a radio-receiving set carried upon said base plate to said speaker housing.

2. A weather-protective radio receptacle for mounting upon cycle vehicles comprising a flat base plate; means for attaching said base plate in a substantially horizontal plane to a member of a cycle vehicle; an open-bottom cabinet including side and top walls detachably carried at the marginal edge portion of said base plate and defining therewith a substantially enclosed chamber for the reception of a radio-receiving set; a hollow metallic housing embodying a parabolic member and a closure grille carried at the open end of said member and defining a substantially enclosed chamber for the reception of a radio loud speaker; a hollow metallic pedestal member electrically connected with said parabolic member and extending through the top wall of said cabinet and within the chamber defined by said cabinet and said base plate; means rigidly connecting said pedestal member to the top wall of said cabinet but electrically insulating said pedestal member from said cabinet; a loud speaker lead extending through said pedestal member and within the chambers defined by said cabinet and said housing and electrically insulated from said housing, pedestal member and cabinet for connecting a loud speaker disposed within said housing with the loud speaker circuit of a radio-receiving set carried within said cabinet; and means electrically connected with said pedestal member internally of said cabinet for connecting the antenna circuit of a radio-receiving set carried within said cabinet with said pedestal member and said housing, the latter serving when so connected as an external antenna for a radio-receiving set disposed within said cabinet.

GRANT L. VAN GASTLE.
